ROSE H. MARTENS, OF COBLEY, OHIO

LINGERIE CLASP

Application filed August 21, 1931. Serial No. 558,441.

This invention relates to lingerie clasps.

The general purpose of the invention is to provide an improved lingerie clasp with which the shoulder straps of one or more undergarments may be easily engaged, from which the straps may be easily disengaged, and through which the straps are freely shiftable to accommodate movements of the body, but which will effectively secure the straps from displacement from the shoulder.

The foregoing and other purposes of the invention are attained in the lingerie clasp illustrated in the accompanying drawing and described below. It is to be understood that the invention is not limited to the specific form thereof shown and described.

Of the accompanying drawing,

Figure 1 is a perspective view of a person showing a shoulder clasp as used to support the shoulder straps of an undergarment;

Figure 2 is enlarged perspective view of the clasp;

Figure 3 is a reduced plan view of the clasp shown in Figure 2 showing the manner in which a shoulder strap is engaged therewith;

Figure 4 is a plan view of a modified form of clasp;

Figure 5 is a section on line 5—5 of Figure 4; and

Figure 6 is a plan view of another form of clasp embodying the invention.

Referring to Figures 1 to 3 of the drawing showing a clasp embodying the invention, a piece of wire is formed with a pointed end portion 10, a loop 11, a shank 12, and a loop 13 which is bent to hook-shape as shown, whereby portion 10 may cooperate therewith providing a safety pin. From loop 10 the wire is formed into an open loop including shank 12, a portion 14 extending laterally of the safety pin, a portion 15 extending longitudinally of the safety pin and a reversely extending portion 16 directed inwardly of the space between shank 12 and the portion 15, the inner end of which is curled as at 17 to avoid tearing a garment.

The loop defined by shank 12 and portions 14, 15, 16 and 17 of the wire is adapted readily to receive the shoulder straps of an

undergarment therein by insertion through the space between portion 16 of the loop and shank 12 of the straps, the straps being doubled or gathered if necessary to pass between the end 17 of the loop and the portion 14 thereof and then spread out under the portion 16 thereof (see Figure 3).

The safety pin of the clasp is secured to the inner side of the shoulder of an outer garment as will be understood and the straps of one or more undergarments may be engaged in the loop thereof as has been described. It will be apparent that due to the open formation of the shoulder strap loop the straps are easily engaged in or disengaged from the clasp and will slide freely therein so as not to apply any strain to the safety pin which would result in bending of the clasp or tearing of the outer garment. However, the strap cannot be displaced from the clasp to either side thereof since it is embraced at the sides by the loop.

In Figures 4 and 5, a shoulder strap loop is shown attached to a standard safety pin to embody the invention. This loop which is designated 20 may be a stamping from sheet metal with a portion 21 adapted to be folded about the shank of a safety pin and, if desired, soldered or otherwise secured to said shank.

In Figure 6, the improved clasp is shown constructed from a single piece of wire and a safety pin hook member. This comprises a single piece of wire with a pointed end portion 30 providing the pin, the safety pin loop 31 and the safety pin shank 32, and the shoulder strap loop is formed by shank 32, a laterally directed portion 33, a portion 34 extending longitudinally of the safety pin, and the reversely bent, inwardly extending portion 35 terminating in the curled end 36.

The safety pin hook member is illustrated at 37 and may be secured to the clasp by a portion 38 crimped or folded about the wire portion 33 and soldered or otherwise secured thereto if desired.

It will be apparent from the foregoing that numerous modifications of the invention may be resorted to without departing from the

spirit thereof or the scope of the appended claims.

What is claimed is:—

1. A lingerie clasp comprising a safety pin and a shoulder strap retaining loop including a portion extending laterally from adjacent one end of the pin, a portion extending longitudinally in spaced relation toward the other end of the pin, and a reversely bent portion extending inwardly of the space between said longitudinally extending portion and said pin, the several longitudinally extending portions being widely spaced, whereby a shoulder strap may be freely engaged in the loop by passing the same between the reversely bent portion and the shank of the pin and between the inner end of the reversely bent portion and the laterally extending portion into the space between the longitudinally extended portion and said reversely bent portion.
2. A lingerie clasp comprising a safety pin and shoulder strap loop including a single piece of wire having a pointed end portion to provide a pin, a safety pin loop, a safety pin shank, a safety pin catch, a portion extending laterally from the shank, a portion extending longitudinally of the shank in spaced relation thereto and a reversely bent portion extending inwardly of the space between said longitudinally extending portion and said shank, the shank and the longitudinally extending and reversely bent portions being widely spaced, whereby a shoulder strap may be freely inserted into the clasp between the reversely bent portion and the shank of the pin and between the inner end of the reversely bent portion and the laterally extending portion into the space between the longitudinally extended portion and said reversely bent portion.
3. A lingerie clasp comprising a safety pin and shoulder strap loop including a single piece of wire having a pointed end portion to provide a pin, a safety pin loop, a safety pin shank, a portion extending laterally from the shank, a portion extending longitudinally of the shank in spaced relation thereto and a reversely bent portion extending inwardly of the space between said longitudinally extending portion and said shank, said shank and said longitudinally extending and reversely bent portions being widely spaced, whereby a shoulder strap may be freely inserted into the clasp between the reversely bent portion and the shank of the pin and between the inner end of the reversely bent portion and the laterally extending portion into the space between the longitudinally extended portion and said reversely bent portion, said safety pin having a catch associated therewith.
4. A lingerie clasp comprising a safety pin and shoulder strap loop including a single

piece of wire having a pointed end portion to provide a pin, a safety pin loop, a safety pin shank, a loop on said safety pin shank bent over to provide a safety pin hook member, a portion extending from the hook member laterally of the shank, a portion extending longitudinally of the shank in spaced relation thereto and a reversely bent portion extending inwardly of the space between said longitudinally extending portion and said shank, said shank and said longitudinally extending and reversely bent portions being widely spaced, whereby a shoulder strap may be freely inserted into the clasp between the reversely bent portion and the shank of the pin and between the inner end of the reversely bent portion and the laterally extending portion into the space between the longitudinally extended portion and said reversely bent portion.

5. A lingerie clasp comprising a safety pin and shoulder strap loop including a single piece of wire having a pointed end portion to provide a pin, a safety pin loop, a safety pin shank, a portion extending laterally from the shank, a portion extending longitudinally of the shank in spaced relation thereto and a reversely bent portion extending inwardly of the space between said longitudinally extending portion and said shank, said shank and said reversely bent portion being widely spaced, whereby a shoulder strap may be inserted into the clasp between the reversely bent portion and the shank of the pin and between the inner end of the reversely bent portion and the laterally extending portion into the space between the longitudinally extended portion and said reversely bent portion, said safety pin having a catch associated therewith.

6. A lingerie clasp comprising the combination with a safety pin, of means defining an open loop in association with the shank of said pin and having a reversely bent, inwardly directed portion to engage about a shoulder strap inserted therein, said portion being widely spaced from the shank of said safety pin to permit free insertion of the shoulder strap.

7. A lingerie clasp comprising an open loop to receive a shoulder strap having a portion extending inwardly of the loop substantially in the plane thereof and widely spaced from the other portions of the loop to embrace a shoulder strap inserted therein, whereby the shoulder strap may be passed freely into the loop and will slide freely therein, and means for securing the loop to a garment.
